STORE FRONT CONSTRUCTION

Francis J. Plym, Niles, Mich., assignor to The Kawneer Company, Niles, Mich., a corporation of Michigan

Application June 22, 1935, Serial No. 27,885

6 Claims. (Cl. 20—56.4)

The present invention relates to store front constructions and more particularly to a novel sash structure and means for mounting and retaining a pane of glass in proper adjusted position.

Among the objects of the present invention is to provide a novel means and method of retaining a pane of glass in position.

A further object of the invention is the provision of a novel construction of inner and outer sash members and a resilient retaining means for yieldably yet firmly mounting and holding a pane of glass in adjusted position.

Another object of the invention is the provision of a novel combination of glass retaining members adapted to hold a pane of glass with a uniform pressure throughout their length, whereby to eliminate the danger of cracking or splitting of the glass due to an unequal gripping pressure.

In prior constructions, the outer sash member or moulding was made adjustable to move toward or away from the glass by means of screws, cam members or the like. These screws, cam members, etc., were spaced at intervals throughout the length of the sash members and were adjusted until the desired pressure was applied to the pane. Such pressure was dependent upon the workman installing the store front, applying a uniform pressure by adjusting each screw, cam member or the like an equal amount. It will be readily apparent that this was seldom, if ever, accomplished in actual practice, and even though accomplished, pressure was applied at spaced points and not equally over the entire length of the glass.

By means of the present novel construction, suitable retaining pressure is applied to the glass regardless of any variations in thickness. Thus the construction can be standardized for retaining glass even though such glass may vary in thickness.

It is another object of the present invention to provide a novel glass retaining means which permits a perfect mitre at the corners or meeting edges. The outer sash member or moulding is always maintained in perfect alignment and so the meeting edges of adjoining or abutting mouldings always provide an even, perfect alignment and mitre.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawing, and while I have shown therein a preferred embodiment, it is to be understood that the same is susceptible of modification and change, and comprehends other details, arrangements of parts, features and constructions without departing from the spirit of the invention.

In the drawing:

Figure 1 is a fragmentary view in front elevation of a window or store front provided with the novel sash construction.

Fig. 2 is a view in vertical cross section taken in a plane represented by the line 2—2 of Fig. 1.

Figs. 3, 4, and 5 are fragmentary views in perspective of the elements or sections comprising the novel combination.

Fig. 6 is a view in vertical cross section of an alternate sash construction.

Fig. 7 is a view in vertical cross section of a further alternate construction.

Referring more particularly to the disclosure in Figs. 1 to 5, inclusive, of the drawing, the embodiment therein shown comprises a store front construction 1 adapted to form a setting or mounting for a pane of glass 2. The store front construction consists of an inner sash member or pane seating section 3, an outer sash member or moulding 4 and a resilient strip or member 5 for firmly, yet yieldably, retaining the pane in its proper adjusted position.

By means of the present construction and arrangement, the glass is placed under no undue strains and stresses caused by the present universal method of mounting the glass in which screws, cam members or the like are employed in setting the glass. These screws, cam members or other clamping means are employed to exert the necessary holding pressure and are spaced apart at suitable distances along the edges of the glass.

Thus the clamping or holding pressure is applied merely at these spaced points and such pressure is further dependent upon the workman installing the glass, adjusting the screws, cam members or the like. Such adjusting means are seldom, if ever, adjusted to the same degree, and when the glass is placed under undue stresses or strains as by wind or by a person leaning thereagainst, the glass frequently cracks or is damaged.

The present invention eliminates all such objections as the screws, cam members or other like or equivalent adjusting means are eliminated. The glass-holding pressure extends for the length or extent of the glass and provides a line or con-

tinuous surface contact rather than spaced point contacts with the pane.

The pane-seating section or inner sash member 3 is shown as mounted upon a sill 6 and riser 7, 5 and comprises a base portion 8 having a channel or groove 9, and merging or extending into an outer ledge 10, and an upwardly extending projection or flange 11 at the rear thereof which merges into a downwardly extending face 12 having 10 an inwardly extending lip 13 adapted to seat within a notch formed in the riser 7.

The outer sash member or moulding 4 is provided with an upper glass engaging or abutting portion 14, a lower channel portion 15 adapted to 15 receive the ledge 10 of the pane-seating section, and a flange or projection 16 adapted to be received in the channel or groove 9. A suitable sheathing 17 is provided for covering and protecting the sill 6, and is provided with a lip 18 20 adapted to interlock with the downwardly extending leg 19 of ledge 10.

In the assembly of the pane of glass, the sheathing 17 and pane-seating section 3 are mounted upon the sill and riser. The glass is next placed 25 upon strips of leather or the like 20 seating on the base of the section 3. The moulding 4 is next placed in position with its flange or projection 16 forced into the groove 9 as shown in Fig. 2. Next the resilient strip or retaining member 5 30 is pressed or forced downwardly in between the flange or projection 11 and the rear face of the glass. This strip is preferably of suitable spring metal of substantially U-shape as more particularly disclosed in Figs. 2 and 5, and provides an 35 efficient means for firmly retaining the glass in position, yet of sufficient resiliency to permit the glass to yield or flex upon the application of an undue strain thereagainst. The metal of the strip 5 as well as the metal of the sash members may 40 be of any gauge or material suitable for the purpose and both sash members may be rigid.

In Fig. 6 there is disclosed an alternate construction in which the pane-seating section 21 is formed with a glass-holding ledge 22 having an 45 upstanding lip 23, a base 24 provided with an interlocking part 25, and rear or inner projecting part or flange 26, the lower edge or lip 27 thereof being adapted to seat or anchor in a groove formed in the riser 28 of the sill 29.

50 The outer sash member or moulding 30 is provided with a glass abutting lip 31 and an interlocking part 32 adapted to engage with the interlocking part 25 and retain the moulding in its proper position. The upstanding lip 23 provides 55 a retaining means as well as a guide for aligning the leather blocks 33.

In this alternate form of the invention, the resilient strip 34 for retaining the glass may be provided with a groove or recess 35 for seating 60 over and anchoring onto the flange 26 of the section 21, but the function and operation of the strip or resilient member is identical with that shown in Figs. 2 and 5. Also, a wire or rod 36 may be provided for stiffening the angle when there is 65 a mitre, or, if desired, this wire may be replaced by an angle member.

Fig. 7 discloses a further alternate construction in which the sash members 37 and 38 are preferably formed of extruded metal. The inner 70 member or pane seating section 37 is formed with a glass-holding ledge or base 39, having a downwardly turned lip 40 and an inner projecting part or flange 41, this inner sash member seating upon and connected to a riser 42 of a sill 43.

75 The outer sash member or moulding 38 is pro-

vided with a glass abutting or holding portion 44 and a base 45 having an upwardly curved lip 46 and a downwardly or outwardly projecting portion 47. The base flange 41 of the inner sash member and the projection 47 of the outer sash member or moulding are bevelled or mitred to permit a ready assembly of the sash construction and retention of the parts in their adjusted position.

In each of the embodiments of the invention, 10 the inner sash member is mounted in position and the glass is then set upon the leather strips or blocks. The moulding or outer sash member is next placed in position and interengaged or interlocked with the inner sash member and then the 15 resilient strip is forced or pressed into the space intermediate the rear side of the glass and the upstanding flange or projection of the inner sash member.

It will be readily appreciated that the entire 20 adjustment is from the rear of the glass. There are no screws, cam members or other adjusting means to exert an unequal pressure against the glass, but an equalized and continuous pressure is applied throughout the extent of the glass. Also 25 the outer sash members or sections thereof are always in perfect alignment and a perfect mitre results. Although not essential in the present construction because of such perfect mitre, cap members 49 may be provided at the corners if 30 desired.

It is to be understood that the resilient strips which form the gutter of the store front, as well as the outer sash members or mouldings, are provided with openings suitably spaced to permit 35 the proper drainage of condensate, etc., as well as for proper ventilation.

Having thus described the invention—

I claim:

1. In a store front construction, the combination of a pane seating section adapted to be mounted upon a sill or other support and having a flange positioned adjacent to but spaced from the rear of the pane, a base upon which the pane is mounted, a longitudinally extending channel 45 and a ledge; a moulding adapted to be mounted upon said section and having a projection adapted to be received in said channel and a part adapted to overlap and interlock with said ledge; and a resilient member adapted to seat intermediate the 50 pane seating section and rear of the pane for yieldably retaining the pane in position.

2. In a store front construction, the combination of a pane-seating section for supporting a pane of glass and provided with a longitudinally 55 extending, upwardly projecting flange, a moulding having a projection adapted to be received in said section and readily removed therefrom or replaced and when assembled, forming the exposed outer face of the store front construction, 60 and a resilient member adapted to be placed intermediate said flange and glass and bear against a side of said glass with an equal pressure throughout its extent.

3. In a store front construction, the combination of a pane of glass, unitary rigid inner and outer sash members, interlocking projections on 65 said members, an upstanding flange on one of said members forming a channel between it and the side of the glass adjacent thereto, and a resilient 70 member adapted to be forced into said channel and against the flange and the glass for forcing the glass against the other of said rigid members, said resilient member extending for the length of said sash members and adapted to exert 75

a uniform pressure against the glass for the complete length thereof.

4. In a store front construction, the combination of an integral rigid inner pane-seating section, a rigid integral pane supporting molding having a part thereof adapted to interlock with a part on the section whereby to lock said section and moulding together, and means for clamping a pane of glass in adjusted position, said means 10 consisting of a U-shaped resilient strip adapted to be pressed into the space intermediate the pane-seating section and glass and thereby force the glass into contact with the rigid moulding and exert a uniform pressure against the rear face of the 15 glass throughout its extent.

5. In a store front construction, the combination of an inner pane-seating section, a groove formed in said member, an outer moulding so formed as to completely protect the pane-seating 20 section from the elements and having a glass engaging portion and a projection adapted to seat in said groove to retain said section and moulding in assembled relation, and a resilient member for

exerting pressure against the inner surface of the glass, said resilient member being wedged intermediate the pane-seating section and glass.

6. A store front construction providing a setting for a pane of glass and comprising unitary 5 rigid inner and outer sash members formed of extruded metal and providing a pane seating section and a moulding, interlocking parts on the sash members for locking these members in assembled relation, a part on the outer member 10 against which the glass is positioned and for supporting one side of the glass, an upstanding flange on the inner member spaced from the rear face of the glass and forming a recess between it and the glass, and a resilient member adapted to be 15 inserted intermediate the rear face of the glass and the upstanding flange so that a part thereof engages the glass throughout the extent of the setting and exerts a continuous and equalized holding pressure thereagainst, and a part thereof 20 seats within the recess to retain the resilient member in position.
